RADIO RECEIVING APPARATUS

Filed April 20, 1925

UNITED STATES PATENT OFFICE.

HERBERT M. HILL, OF LEONIA, NEW JERSEY.

RADIO RECEIVING APPARATUS.

Application filed April 20, 1925. Serial No. 24,497.

It is an object of the present invention to provide a radio receiving set of extremely simple and light construction which will be thoroughly serviceable in use and which may 5 be manufactured with comparative economy. Another object is to provide a set of the above character, the parts of which may be readily assembled without the need for special tools.

A further object is to provide a receiving 10 set which will be so compact that it may be conveniently closed and carried in a coat or vest pocket and in which the operating parts shall be entirely protected during such transportation.

15 In a preferred specific embodiment of the invention, the set includes a small book-like folder having stiff covers and a limber back. A coil of loosely wound wire constituting an inductance is secured by a strap to one of the 20 covers closely adjacent the limber back, and preferably carries a manually displaceable member in the nature of a movable ring which limits the spreading of the free portions of the coil convolutions and thereby effects adjustment of the inductance coil with a high 25 degree of precision.

According to another preferred feature, attachment means is provided on the folder for attachment of the crystal detector and of the 30 aerial, ground and telephone wire terminals. The attachment means preferably comprises a plurality of clips extending adjacent the free edge and one of the side edges at the inside of one of the stiff covers. Preferably also 35 one of the clips protrudes beyond the attached edge of the cover and serves as a reinforcement for the limber back. When the folder is closed, the covers are spaced apart, a predetermined distance by the clips. Thus 40 the crystal is thoroughly protected against crushing or loss and there can be no distortion of the loose wire inductance coil while it is confined between the covers of the folder.

According to another feature, the crystal is 45 mounted by clamping between spring clamping jaws near one end of a metallic clip, the other end of the clip being provided with means for gripping a conductor.

According to another feature of the invention, 50 the contact or "cat's whisker" is mounted in another clip in such a manner that it may be firmly held in any desired position of adjustment relative to the crystal. The cat's whisker is preferably formed of a thin 55 length of pointed steel from which the temper has been drawn and is so mounted in its sup-

porting clip that it will have a light yet firm engagement with the crystal.

The present application forms a continuation in part of my copending application, 60 Serial No. 583,525, filed August 22, 1922, now Patent No. 1,545,754, granted July 7, 1925, in which the variable inductance is claimed per se, and also of my copending application, Ser. No. 666,666 filed October 5, 1923, to the 65 clip per se.

In the accompanying drawings,

Figure 1 is a perspective view of the set in closed position,

Figure 2 is a plan view of the device in open 70 position,

Figure 3 is a side elevation or edge view showing the inductance coil in one position of adjustment,

Figure 4 is a sectional view on the staggered 75 line 4-4 of Figure 2 showing the coil in another position of adjustment, and

Figure 5 is an end view of the device in closed position,

Referring now to the drawings, I have 80 shown a small folder which may be of cardboard or any other inexpensive material comprising relatively stiff covers 10 and 11, and a limber or flexible back 12 connecting the covers. Upon the inside of this folder, I 85 mount the variable inductance coil, a detector and the various terminal members for the connection of the antenna, ground and telephone wires.

The variable inductance comprises a loosely wound coil 13 formed of a single length of enameled wire preferably retained in position by strap 14 having its flexible intermediate portion encircling the coil and having its ends held together and to the cover 10 by 90 a rivet or other securing device 15. The rivet 15 is arranged closely adjacent the edge of the cover 10 so that the coil encircling strap 14 normally extends over the flexible back 12. By thus arranging the coil, I reduce the 100 necessary distance between the back and the cover edges to a minimum for any given size of coil and tend toward compactness of the set. The strap is of sufficient size to snugly hold contiguous portions of the coil 105 convolutions together while the non-contiguous portions are free to spread and separate as indicated in Figures 3 and 4, to an extent which is predetermined by a movable adjusting strap or ring 16 encircling the coil. Strap 110 16 is substantially similar to the strap 14 except that its free ends are merely riveted to-

gether at 17 and not anchored to a cover. The normal tendency of the coil convolutions is to spread apart and when the strap 16 is moved to a position diametrically opposite 5 the strap 14, this spread is reduced to a minimum or in other words, is negligible. When however, the strap 16 is moved to a position immediately adjacent, the strap 14, the coil convolutions may freely spread with respect 10 to the strap 14 as an axis. Any intermediate position of the strap 16 will serve to adjust the self-inductance of the coil so that tuning may be accomplished with great precision. Apparently the inductance is a maximum 15 when the coil is in its normal collapsed position and is reduced as the convolutions are spread apart, and is apparently a minimum when the coils are symmetrically disposed with respect to the two covers of the folder 20 as indicated in Figure 4. The inductance may also be changed by varying the distribution of the convolutions; i. e. making them more compact at one region and spacing them further from each other in any other region. 25 Obviously further variation may be effected by pressing upon the coils to change their form or shape.

It will be noted that the connected ends 30 of the strap 16 afford a convenient handle for shifting the position of this adjusting member. The inductance coil may be spread through even a greater angle than the 180° angle shown in Figure 4 if the folder 11 is supported adjacent the edge of a table as by 35 a suitable weighted retaining device and the cover 10 permitted to hang down below the edge of the table. It is desirable that the strap 14 exert sufficient pressure on the coil convolutions at their point of contiguity to 40 impart a normal spreading tendency to the non-contiguous free parts of the convolutions.

The mounting means for the crystal 18 which serves as the detector is preferably a 45 gripping member, the base 19 of which is riveted at 20 to the cover 10 of the folder and extends parallel to the shorter edge thereof, closely adjacent thereto. The preferred clip member shown comprises integral ears 21 standing from the members 19, the jaw 22 of 50 the clamp being pivoted at 23 between the ears 21 and urged by an expansion spring 24 into coaction with jaw teeth 25 formed at the free end of base 19. The crystal 18 is thus firmly 55 held between the clamping jaws by the expansion of the spring 24. The other end of the base 19 is preferably a conventional Fahnestock clip 26, of well known construction for 60 gripping the ground terminal. The curved end of the Fahnestock clip projects over the inner edge of the cover 10 and acts as a stiff reinforcement about which the limber back is folded as the covers are swung toward 65 closed position.

65 The base member 19 is shown as an integral

piece extending from the jaw 25 and reversely bent at 26 but it will be apparent that the device may be made of composite construction so as to utilize standard clip elements.

Along the inside of the free edge of the 70 cover 10 I provide a pair of double ended Fahnestock clips 32, 33 of conventional construction which extend substantially the entire length of the cover and are spaced from each other. These clips may be conveniently 75 secured to the cover by rivets 34 or other appropriate securing devices. The two adjacent clip elements 35 and 36 preferably hold the terminals of the telephone wires (not shown). Clip element 37 is used for making an aerial 80 connection, and clip element 38 holds the contact pin or cat's whisker, which latter may be conveniently formed by bending into general **U** shape, a finely pointed steel needle from which the temper has been drawn. The shorter 85 leg 39 of the **U** is held by the clip and the longer leg 39^a of the needle projects from the clip and is bent at right angles adjacent the point. This construction causes the point of the needle to bear with a slight spring pressure against the crystal, and for all ordinary 90 purposes of adjustment, it is not necessary to touch the holding clip. The bent intermediate portion of the cat's whisker may be manually depressed to effect elevation of the contact point and swinging the same over a new point on the crystal with which contact is to be made when pressure on the bent end is relieved. Of course, major adjustment of the 95 whisker may be made by depressing the finger piece of the clip element 38, manually changing the position of the whisker and then releasing the finger piece to reclamp it in position. The Fahnestock clips constitute a reinforcement for the covers to prevent flexing 100 thereof, and act as spacers to limit the relative approach of the covers and to prevent undue 105 pressure on the receiving apparatus by the covers when the set is shipped or transported.

In a folded set, none of the receiving apparatus projects beyond an edge of the cover. There is no danger of the cover pressing the clamping jaws against the crystal since under normal conditions of transportation the telephone wires are removed from their holding 110 clips which latter are free to spread wide apart and contact the cover before it can press upon the crystal clamping jaws. With the adjusting strap 16 in the position of Figure 2, the inductance coil will be reduced to a thickness less than the clips which act as cover stops and there will be no danger of coil distortion.

The clip 19 is capable of general application 115 independently of the receiving set. One desirable application is in effecting the connection of an ordinary B battery. When used for this purpose, gripping jaws 19, 22 clip the terminal and the lead wire from the battery is held in the Fahnestock clip element 26. 120 125 130

If the jaws 19, 22 are of larger proportions, they might also be used for embracing a grounding metallic pipe while clip element 26 grasped a ground wire from a set.

5 The covers may be conveniently held in closed position by any suitable means as for instance, the strap 40 connected at one end to cover 10 and carrying at its free end a separable fastener element 41 for coaction with a 10 mating element 42 on the outside of cover 11.

It will thus be seen that the herein described apparatus in which the several features of this invention are embodied, and which apparatus in its action attains the various objects of the invention and is well suited to 15 meet the requirements of practical use.

As many changes could be made in the above construction, and many apparently widely different embodiments of this invention could be made without departing from 20 the scope thereof, it is intended that all matter contained in the above description or shown in the accompanying drawings shall be interpreted as illustrative and not in a limiting 25 sense.

Having thus described my invention, what I claim as new and desire to secure by Letters Patent is:—

1. In a radio receiving set, in combination a 30 folder, a coil of loosely wound wire confined between the covers of the folder, strap means through the coil fixing the said coil to the folder adjacent the back thereof, a metal clip member secured to the inside of one of the 35 covers of the folder adjacent one of the edges thereof and having a pair of jaws for gripping a crystal, a pair of metallic clip members secured to the side of said folder adjacent an edge thereof, one of said clips sustaining a 40 contact member for contact with the crystal, and contact means for a telephone wire, the other clip serving for connection with the other telephone wire.

2. In a radio receiving set, in combination a 45 folder, a coil of loosely wound wire confined between the covers of the folder, strap means through the coil fixing the said coil to the folder adjacent the back thereof, a metal clip member secured to the inside of one of the 50 covers of the folder, adjacent one of the edges thereof and having a pair of jaws for gripping a crystal, a pair of metallic clip members secured to the side of said folder adjacent an edge thereof, one of said clips sustaining a 55 contact member for contact with the crystal, and contact means for a telephone wire, the other clip serving for connection with the other telephone wire, an adjusting strap slideable on the wire coil and operative when in 60 position diametrically opposite the retaining strap to reduce the coil to a thickness less than the space between the closed covers whereby the coil cannot be distorted by the covers.

3. In a radio receiving set, in combination a 65 folder, a coil of loosely wound wire con-

fined between the covers of the folder, strap means through the coil fixing the said coil to the folder adjacent the back thereof, a metal clip member secured to the inside of one of the covers of the folder adjacent one of the 70 edges thereof and having a pair of jaws for gripping a crystal, a pair of metallic clip members secured to the side of said folder adjacent an edge thereof, one of said clips sustaining a contact member for contact with the crystal and contact means for a telephone wire, the other clip serving for connection with the other telephone wire, the contact means for the telephone wire being adapted to spring upwardly when the wire is removed 75 therefrom, and project beyond the plane of the crystal retaining means whereby the telephone wire contact means limits the closing movement of the folder to prevent crushing of the crystal. 80

4. In a radio receiving set, in combination a folder, a coil of loosely wound wire confined between the covers of the folder, strap means through the coil fixing the said coil to the folder adjacent the back thereof, a metal clip member secured to the inside of one of the covers of the folder adjacent one of the edges thereof and having a pair of jaws for gripping a crystal, a pair of metallic clip members secured to the side of said folder adjacent an edge thereof, one of said clips sustaining a contact member for contact with the crystal and contact means for a telephone wire, the other clip serving for connection with the other telephone wire, the back of the folder being limber and one of the clip members including a rounded end projecting over the inside edge of a folder cover to reinforce the limber back when the folder is closed. 90

5. In a radio receiving set, in combination a folder, a coil of loosely wound wire confined between the covers of the folder, strap means through the coil fixing the said coil to the folder adjacent the back thereof, a metal clip member secured to the inside of one of the covers of the folder, adjacent one of the edges thereof and having a pair of jaws for gripping a crystal, a pair of metallic clip members secured to the side of said folder adjacent an edge thereof, one of said clips sustaining a contact member for contact with the crystal and contact means for a telephone wire, the other clip serving for connection with the other telephone wire, the contact member for the crystal comprising a substantially U shaped length of wire having one leg held by its clip and including a pointed end spring pressed against the crystal, said contact member being held at a distance from the folder back, less than the thickness of the telephone wire clips. 100

6. A radio receiving set including a pair of relatively stiff covers and a back connecting them, a clip supported on the inner face 105

of one of the covers and a crystal held in the 5 clip, a second double ended clip arranged closely adjacent the free edge of the cover and mounting at one end a cat's whisker, the other end of said double ended clip constituting a stop to limit the closing movement of the cover and protect the crystal and cat's whisker against crushing.

7. A radio receiving set including a pair 10 of relatively stiff covers and a back connecting them, a clip supported on the inner face of one of the covers and a crystal held in the clip, a second double ended clip arranged closely adjacent the free edge of the cover 15 and mounting at one end a cat's whisker, the other end of said double ended clip constituting a stop to limit the closing movement of the cover and protect the crystal and cat's whisker against crushing, said cat's whisker 20 including an approximately U shaped length of wire having its intermediate portion disposed closely adjacent the free edge of the cover.

8. A radio receiving set including a folder 25 having stiff covers and a limber back, an inductance coil anchored to one of the covers closely adjacent the inner edge thereof, adjusting means for regulating the spread of the free edges of the convolutions of said 30 coil, a plurality of terminal clips arranged along the edges of the inside of one of the

covers, certain of said clips mounting a crystal and a cat's whisker, certain of said clips being adapted for connection with aerial and ground leads, certain of said clips being 35 adapted for connection with a telephone, the last mentioned clips being adapted to normally spring open when unconnected to a telephone, whereby they serve to limit the closing movement of the covers and prevent 40 the covers from contacting with the other clips and the inductance coil.

9. In a radio receiving set, a crystal, a cat's whisker coacting with the crystal, said whisker including a length of wire bent into 45 approximately U shape having a turned over pointed end contacting with the crystal, a spring clip retaining the shorter leg of the U in such position that the pointed end of the whisker lightly contacts the crystal and in 50 such position that the intermediate portion of the U is free for spring depression to effect elevation of said point off the crystal.

10. A device of the class described in claim 55 8 wherein the clip which receives the aerial lead extends over the inner edge of the cover to reinforce the limber back when the device is in folded position.

Signed at New York city, in the county of New York and State of New York, this 18th 60 day of April, A. D. 1925.

HERBERT M. HILL.
